UNITED STATES PATENT OFFICE.

HERBERT J. PERCY, OF LYNN, MASSACHUSETTS, ASSIGNOR TO UNITED SHOE MACHINERY COMPANY, OF PATERSON, NEW JERSEY, A CORPORATION OF NEW JERSEY.

SHOE.

1,141,911.

Specification of Letters Patent.

Patented June 1, 1915.

Application filed September 9, 1910. Serial No. 581,179.

To all whom it may concern:

Be it known that I, HERBERT J. PERCY, a subject of the King of England, residing at Lynn, in the county of Essex and State of Massachusetts, have invented certain Improvements in Shoes, of which the following description, in connection with the accompanying drawings, is a specification, like reference characters on the drawings indicating like parts in the several figures.

This invention relates to shoes and particularly to welt shoes. In the manufacture of these shoes an innersole is used upon the bottom face of which from the heel seat 15 around the forepart, is raised by channeling or otherwise, a lip or shoulder and to the outer face of this lip the stretched or lasted upper is sewed, together with the welt by which the outersole is later to be connected 20 to the shoe. The process of lasting or stretching the upper over the last and working it into position to be secured is usually accompanied or followed by the application of temporary fastening means such as tacks 25 which hold the upper while it awaits presentation to the sewing machine. With the upper materials of the rear portion of the shoe is included a heel stiffener the body portion of which stands up between the upper 30 and lining around the heel of the wearer's foot and the flange of which is turned inwardly under the foot. This stiffener is made of some slightly flexible material such as stiff sole leather or leather-board which 35 is commonly prepared by compression and molding to reduce flexibility and increase shape retaining qualities. These processes and the nature of the material are such that the stiffener is usually found to be hard and 40 not readily penetrable and to have a smooth surface.

The attaching flange of the heel stiffener is molded, or is bent in the lasting operation, to lie flat down upon the heel seat end of the 45 innersole to which it is attached, together with the lasted-over upper, by lasting tacks. These tacks of the heel seat are permanent fastenings, fully driven and clenched on the sole plate of the last, as contrasted with the 50 lasting tacks of the shank and forepart which are only partially driven in anticipation of their withdrawal when their temporary use has been fulfilled. The wings or 55 sides of the stiffener extend forwardly beyond the heel seat and into the shank and the

flange is included in the rear portion of the "inseam", as the stitching is called which connects the upper and the welt to the inner-sole lip. In practice difficulty has been encountered in sewing the end portions of the 60 inseam and in obtaining a snug fitting of the upper of the finished shoe at these portions of each side of the shoe. The flange of the stiffener overlies the lip of the innersole and it bridges from the edge of the innersole up over 65 the lip at a small angle to the path of the sewing machine needle and its hard smooth surface causes the needle to tend to slide along it without penetrating it. To lessen 70 this tendency the operator changes the inclination at which he holds the shoe in order to present the hard material more nearly perpendicular to the path of the needle. In thus changing the inclination of the work 75 the shoe is fulcrumed on the lower end of the channel guide, which is located at the inner side of the lip, and thereby the needle is also caused to enter the stock higher up on the lip whereas it should sew the stitch close 80 down at the foot of the lip in order to make a firm connection with the innersole. The result is that the pressure applied to the shoe in the heel attaching operation spreads 85 this loosely attached portion causing a mis-shaping of the shoe at this point. Special machines have been devised to tighten this stock over the last bottom, crush it down while held tightened and tack it in place. Another difficulty is that in stitching the 90 first end of the inseam it is impracticable to get the sewing instrumentalities into position to begin the inseam close up to the adjacent fully driven heel seat tack and again in stitching the last end of the inseam the channel guide encounters the portion of the heel 95 stiffener flange that is held down by the adjacent heel seat tack. This leaves a gap between the last stitch and the first tack, and the channel guide also frequently pries up and loosens the tack. This adds to the need 100 for retightening and further tacking which has come to be a general practice. By the present invention these manufacturing difficulties are obviated or very substantially reduced and the shoe is materially improved in 105 appearance and strength and in accordance with a preferred embodiment of the invention, certain additional manufacturing advantages are secured which will be later explained.

A very important feature of this invention consists in a heel stiffener having that portion of its flange which is to be incorporated in the inseam formed to fit against the outer side of the innersole lip. Preferably the stiffener is molded to shape a portion of its flange to lie flat upon the feather of the innersole and a portion to stand upright as a lip-against the lip of the innersole. The width of the flat portion should for the best results correspond with the width of the feather. These molded portions of the stiffener will preferably extend from the end of each wing back as far on the shoe as the innersole lip extends or to the location for the first heel seat tack.

Another important feature of this invention consists in a shoe stiffener having an abrupt edge to indicate the proper point for a subsequent operation upon the shoe in which the stiffener is incorporated, herein shown as formed by an incision made through the inner or marginal portion of an inturned flange of the stiffener between that portion of the stiffener which is to be tacked down upon the heel seat of the shoe and that portion which is to be sewed into the inseam. This incision, in the case of a stiffener which includes an upturned lip to stand against the rib of an innersole may advantageously form the division between the upturned lip and the rear portion of the flange, thus avoiding the necessity for an abrupt bend in the flange.

While the formation of an upturned lip on the stiffener flange in the manner above explained greatly facilitates the sewing of the ends of the inseam and enables the stitches to be located close down in the angle between the horizontal and upright surfaces of the innersole, and the corresponding faces of the flange, the use in this form of stiffener of an incision separating the upturned lip from the flat portion of the flange that is tacked down is a further important advantage in the sewing operation. This separation enables the stitch forming devices to locate a stitch at the very end of the stiffener lip, which may be closely adjacent to the heel seat tack so as to leave no gap between the two kinds of fastenings. The inseam may also be continued to the end of the lip on the second side of the shoe, allowing the channel guide to pass out of the channel and over the tacked down portion of the flange without any interruption. The incisions in the stiffener flange may serve this purpose to a greater or less degree even without the additional feature of turning up the portions of the flange in front of the incisions.

Another purpose of great practical importance served by the incisions as above described is that they constitute predetermined starting and stopping points for the inseam. By the use of markings for the inseamer he

can commence and end his seam at the same distance from the heel end of the shoe on both sides and he can inseam successive shoes uniformly. Certain advantages for this will be obvious and to those familiar with this portion of the process of shoemaking it will also be apparent that by the use of this invention the need, now frequently met, will not arise for trimming back one end of the welt and its attaching stitches to obtain uniformity on the two sides of the same shoe. Many operators now begin the inseam farther back on one side of a shoe than the point at which they terminate it on the other side and so necessitate extra work in the welt butting operation. It will therefore be understood that it is a broad feature of this invention to provide a shoe with indications or marks to show the location for the ends of the inseam and that such marks or position indications may be found in the incisions or in the ends of the stiffener lips if no incisions are made and also such "marks" may take various other forms within this invention.

A further advantage of this invention is found in the shank stiffening effect obtained by the upright longitudinally extending lips of the heel stiffener at each side of the rear part of the shank. A shoe having this heel stiffener may be made with a lighter and cheaper shank stiffener.

The foregoing and other features and advantages of this invention will now be more fully described in connection with the accompanying drawings and will then be pointed out in the claims, except as relates to the novel method herein disclosed which is claimed in a divisional application, Serial No. 644,498, filed Aug. 17, 1911.

Figure 1 is a plan view of a shoe having the upper materials, including the novel heel stiffener, assembled on a last, parts being broken away to show the new features more clearly. Fig. 2 shows the shoe after one side has been lasted and the other side lasted and the weltling operation commenced, the needle and the channel guide of the sewing apparatus being shown in operative relation to one another and to the work. Fig. 3 illustrates a portion of the last, heel stiffener, upper and welt showing the close fitting of the parts held by the inseam.

The last is indicated at 2, the innersole at 4, the lip thereof at 5, and the feather at 6.

The present invention relates to novel formation of the front or wing portions of a heel stiffener and in the broader aspects of the invention the rear or body portion of the stiffener may have any usual or suitable shape.

The front portions or the wings of the stiffener are provided with inturned flanges 8 and upturned lips 10 located inwardly from the fold over the edge of the shoe

bottom preferably a distance equal to the width of the feather of the innersole. The stiffener is thus provided upon its wings with portions that are adapted to extend 5 upwardly above the plane of the heel seat and that stand inwardly away from the adjacent portion of the upper of a pulled over shoe in position to facilitate the operation of grasping the flange of the stiffener 10 to pull up the wings. The lips 10 extend backwardly from the front ends of the wings as far as the lips 5 of the innersole go and are formed to fit smoothly against the outer face of said lips 5. In the illustrated embodiment of the invention the flange 8 is extended around the rear portion 15 of the heel where it is molded to lie substantially flat upon the heel seat portion of the innersole, and the lip 10 may merge 20 into the margin of the rear portion of the flange by a bend in the material but preferably it is separated therefrom by a cut or incision at 15.

The shoe is assembled upon the last as 25 usual and the upper materials may be secured in assembled relation for the pulling-over and lasting operation by tacks located as shown in Fig. 1 or in any other suitable location. In the lasting operation the flange 30 of the rear part of the heel stiffener is lasted down upon the heel seat end of the innersole and tacked, Fig. 2, as usual and also is lasted down upon the feather of the innersole while the lips 10 are lasted firmly up against 35 the outer face of the innersole lips 5. The lipped formation of the flange enables it to conform closely to the angular faces of the feather and lip of the innersole instead of bridging from the innersole edge to the top 40 of the lip as heretofore. When the shoe is presented to the welter for sewing the inseam the needle 16 approaches the hard material of the heel stiffener lip 10 in a direction substantially perpendicular to the 45 plane of said lip and readily penetrates it. The lasting of the upper and the stiffener flange down into the angle between the feather and lip of the innersole permits the stitches to be sewed down in said angle so 50 that a connection of the parts of the shoe by these stitches is made which is as firm as or firmer than that at any other portion of the inseam. The upstanding lips 10, particularly when bound into place by the 55 stitches, form an effectual stiffener for the shank of the shoe because of the well known resistance offered by stiff sheet material to bending edgewise. The incisions facilitate the commencement of the inseam with a 60 stitch located at the very end of the lips 5 and 10 and close to the heel seat tack. The incision on the second side of the shoe where the inseam is ended enables the channel guide 18 to pass without obstruction out of 65 the inner channel of the innersole and over

the portion of the stiffener flange which has been tacked down. This prevents the channel guide from prying up the heel seat tack as heretofore and also it enables the inseam to be continued to the end of the lips 5 and 70 10 thus attaching the upper completely without the interval which has been necessary between the tack and the last stitch and which required the insertion of an upper fastening tack after the inseam sewing operation. Inasmuch as the operator has not been obliged to tip the shoe down over the channel guide as a fulcrum in order to present the work so that the needle would penetrate the stock instead of sliding along the 75 hard stiffener the stitches have been located close down at the base of the innersole lip and there is no looseness of the upper that requires to be tightened after the inseaming operation, nor is there any chance for 80 the upper to bulge or spread outwardly under the heel attaching pressure because it is firmly attached to the base of the innersole lip and cannot move outwardly as it could if attached to the upper edge of the 85 lip which can tip sidewise. Another advantage is found in the compactness of the stock at the shank and heel breast which is obtained by fitting the stiffener flange firmly down upon the innersole feather. This 90 brings the upper and the welt nearer to the plane of the innersole, giving a "closer" rand crease and allowing the inseam to be 95 trimmed more closely and also avoiding danger heretofore existing of cutting the 100 inseam stitches while trimming the inseam at the ends. A further advantage is in the use of the incisions 15 as guides for the operator in starting and finishing the inseam at predetermined points on each side 105 of the shoe and at the same distance from the heel end of all shoes of the same size. This purpose may well be served by the provision of an abrupt edge in the margin of the stiffener, however it may be formed. 110 The incisions 15, or their equivalents, like the lips 10 may be made during the manufacture of the heel stiffeners and as a part of the molding or some other making operation. To mold a heel stiffener to present 115 at its ends an upstanding lip extending backwardly as far as the lip of the innersole and adapted to stand against the outer face of the innersole whereby the stiffener flange conforms to the shape of the feather 120 and lip when the stiffener is assembled in a shoe is a new step in the manufacture of shoes.

Having explained the nature of this invention and described how it may be employed I claim and desire to secure by Letters Patent of the United States all the protection to which the invention which I have disclosed is entitled over the prior art and the annexed claiming clauses are to be 130

interpreted broadly as an attempt to define rather than to prescribe what the patent covers.

I claim—

5. 1. A heel stiffener having an inturned flange the edge of which at the rear portion of the heel is formed to lie flat upon the heel seat and is coterminous with the stiffener, said edge being turned upwardly from adjacent the breast line of the heel to the ends of the stiffener to present lips for attachment to the rear portions of a welt innersole lip.
10. 2. A heel stiffener having an inturned flange formed with upturned lips which extend from the front ends of the stiffener rearwardly and terminate at points remote from the rear end of the stiffener.
15. 3. A heel stiffener having a short upstanding lip at each end portion and an inturned flange that extends from the rear of the upstanding lip on one end portion of the stiffener around to the rear of the upstanding lip of the other end portion of the stiffener, said flange being formed to lie throughout its width substantially flat upon the heel seat of a shoe and having its inner edge coincident with the terminal edge of the stiffener.
20. 30. 4. A heel stiffener formed to present on a wing portion thereof an abrupt edge visible to the inseam sewing machine operator and located to serve as a guide for the operator in beginning and terminating the inseam.
25. 5. A heel stiffener having an inturned flange and a lip upturned from the edge of the flange at the end portion of each wing and terminating at a point remote from the rear end of the stiffener, each of said lips being separated by an incision from the edge portion of the flange in the rear thereof.
40. 6. A heel stiffener having a flange with an opening formed therein at a point between that portion of the stiffener which is to be tacked down upon the heel seat and that portion which is to be sewed into the inseam, whereby the channel guide of the sewing machine may pass through said flange and the inseam may be continued to a point close to the tacked down portion of the stiffener.
45. 7. In a shoe an innersole having a plane heel seat portion and an upstanding lip located at a substantial distance inwardly from the edge of the innersole and terminating at the heel seat, and a heel stiffener having at the front end of each wing an upstanding lip formed and located relatively to the body of the stiffener to adapt it to stand against the outer face of the innersole lip, and an inturned flange extending around the edge of the heel seat and shaped to lie flat against the heel seat throughout the width of the flange.
55. 8. A lasted shoe to be welted provided on each side of the heel portion with an upstanding lip of the heel stiffener extending rearwardly from the front end of the stiffener wing and terminating at a point remote from the rear end of the stiffener with an abrupt end face in position to indicate to the sewing machine operator the point for beginning or ending the inseam.
60. 9. A molded shoe stiffener having along its entire bottom edge an inwardly projecting flange and provided on the end portions only of the flange with shoulders shaped to fit against a rib formed on a shoe innersole.
65. 10. A lasted shoe to be welted having, in combination, an innersole formed with a feather and a welt and upper attaching rib, and a shoe end stiffener having a flange extending from the bottom edge of the stiffener widthwise of the stiffener and shaped to lie flat upon the feather of the innersole throughout the width of said flange except where the flange encounters the innersole rib and to present adjacent to the rib an upturned portion shaped to fit snugly against the outer side of the rib so as to permit a tight welt attaching seam to be sewed and prevent straining the stitches of the seam after the sewing operation.
70. 11. A heel stiffener having on its bottom portion an inturned flange provided near the ends of the stiffener wings with upstanding lips, that terminate at points remote from the rear end of the stiffener, that portion of the flange at the rear of said lips extending farther inward than the portions that lie between said lips and the sides of the stiffener and shaped to provide a substantially flat heel seat at the rear of said lips.
75. 12. A shoe having an innersole formed with a plane heel seat portion and an upstanding lip located inwardly from the edge of the innersole and terminating at the heel seat, and a heel stiffener having on its bottom at the front end of each wing an inwardly projecting angular portion shaped to fit closely in the angle formed by said upstanding lip and the bottom of the innersole and secured to said lip by a row of stitches, each of said angular portions terminating at a point adjacent to the breast of the heel, said stiffener having at the rear of said angular portions an inturned flange shaped to lie flat upon the heel seat and coterminous with the edge of the stiffener.
80. 13. A molded shoe stiffener having on an end portion thereof a flange projecting inwardly at the bottom of the stiffener and provided with an upstanding lip or edge portion that terminates at a point remote from the rear end of the stiffener.
85. 14. A heel stiffener having on its wings molded portions, each comprising an inturned flange shaped to lie upon the feather
90. 95. 100. 105. 110. 115. 120. 125. 130.

of an innersole and an upturned lip at the inner edge of the flange, said portions of the stiffener extending from the front ends of the wings rearwardly and terminating at points remote from the rear end of the stiffener.

15. A heel stiffener having in its rear portion a flange, including the inner terminal edge of the stiffener, molded to lie flat on the margin of the heel seat substantially parallel to the heel seat, and having at its forward ends upwardly extending portions shaped to stand inwardly away from the adjacent shank portion of the upper of a pulled over shoe and with their edges extending above the heel seat.

16. A heel stiffener molded to present in its rear bottom portion an inturned flange the inner edge of which is coincident with the terminal edge of the stiffener, said flange being shaped to lie wholly upon the margin of the heel seat of a shoe, and the stiffener having upon its wings portions shaped to stand substantially upright from the plane of the heel seat.

17. A heel stiffener having on each wing a narrow inturned flange shaped to lie down upon the feather of a welt shoe innersole and to terminate at or adjacent to the breast line of the heel seat, said stiffener comprising stock of suitable width to form, from the termination of said narrow flange on one wing around the heel seat to the beginning of the narrow flange on the other wing, a relatively wider flange adapted to be tacked down upon the heel seat by the usual lasting tacks located inside the location for the heel attaching nails of the shoe.

18. A heel stiffener molded to present at the front end of each wing a lip formed and

located relatively to the body of the stiffener to adapt it to stand against the outer face of the innersole lip and terminating at a point remote from the rear end of the stiffener.

45

19. A lasted shoe comprising an innersole and upper materials including upper stock and a heel stiffener, said shoe having a portion of the upper materials standing up from the plane of the innersole face and provided with an abrupt edge located in position to be visible to the inseam sewing machine operator while holding the shoe with its side face toward him and designating that point in the length of the shoe at which to begin 55 or end the inseam.

20. In combination, an insole having ribs terminating at the heel portion thereof, a counter stiffener having a seat arranged to engage the marginal edge of the heel portion 60 of the insole and extending to and engaging the rear ends of the ribs, narrow seats located on the stiffener inwardly beyond said first named seat, and arranged to engage those portions which lie between the ribs 65 and the lateral edges of the insole and vertically straight attaching flanges located at the inner edges of and arranged at right angles to said narrow seats, said flanges lying flush with the outer sides of the ribs 70 and having a greater vertical extent than said ribs.

In testimony whereof I have signed my name to this specification in the presence of two subscribing witnesses.

HERBERT J. PERCY.
